TRAIN DISPATCHING SYSTEM FOR RAILROADS

Filed Sept. 21, 1927

UNITED STATES PATENT OFFICE.

SEDWICK N. WIGHT, OF ROCHESTER, NEW YORK, ASSIGNOR TO GENERAL RAILWAY SIGNAL COMPANY, OF ROCHESTER, NEW YORK.

TRAIN-DISPATCHING SYSTEM FOR RAILROADS.

Application filed September 21, 1927. Serial No. 221,038.

This invention relates to train dispatching systems, and more particularly to means for electrically indicating the direction of traffic set up as determined by the sequence of lever movements.

This invention is an improvement on the system disclosed in my prior application Ser. No. 120,423, filed July 3, 1926, and this application is a continuation-in-part of said prior application. The improvement is more particularly directed to the features shown in Figs. 11 to 15 inclusive of said prior application.

In accordance with the present invention it is proposed to use incandescent electric signal lamps having arrows suitably engraved in bull's eyes disposed in front of such lamps to indicate the direction of traffic set up, instead of having the direction arrows engraved on suitable movable signal plates as shown in the prior application above referred to.

Other objects, purposes and characteristic features of the invention will appear in part as the description thereof progresses and will in part be obvious from the accompanying drawings.

In describing the invention in detail reference will be made to the single accompanying drawing, in which a portion of a miniature track diagram located in the dispatcher's tower has been shown on which indicators controlled in accordance with the present invention have been shown, and of which system a portion of the outlying railway track has been shown to indicate how the levers in the tower may control the signals and switch machine of the system.

In said prior application the direction of traffic is set up on the main track of a passing siding and on a single track section of a signaling system of the absolute-permissive-block type having signals 1, 1A, 2, 2A, 3, 4, 5, 6, 7, 7A, 8 and 8A, in accordance with the sequence in which the control relays located at wayside stations adjacent the entrances to passing sidings are energized. For convenience, a portion of the A. P. B. system has been shown conventionally in this application by illustrating the permissive signals 3, 4, 5, and 6 and the stop and stay signals 1, 1A, 2, 2A, 7, 7A, 8, and 8A, together with the control relays Z^0 , Z and Z^1 , and with the signals shown conventionally identified by the same reference characters as the signals in the prior application.

Each of the levers L^0 , L and L^1 is provided with contacts 10, 11 and 12, similarly distinguished by exponents, of which the contacts 12^0 , 12 and 12^1 are connected to line wires 15⁰, 15 and 15¹ respectively for energizing the control relay Z^0 , Z and Z^1 to the right or left hand position depending upon whether these levers are moved to the right or left hand position. In this connection it may be pointed out that the letter B represents the positive side of the suitable source of current, the letter N represents the negative side of said source of current, which source of current has a middle or neutral terminal connected to a common return wire C at which the circuits for the control relays Z terminate.

It is considered expedient to briefly point out how the sequence of lever movements, and in turn sequence of control relay energizations, determine the direction of traffic set up in the system of my prior application conventionally shown herein. The signal system shown in the drawings is one of the absolute-permissive-block type used for single track railways in which the starting signals, such as signals 2 and 2A are so interlocked with the starting signals 7 and 7A through the tumble down circuit for the west bound intermediate signals 5 and 3 and the tumble down circuit for the east bound intermediate signals 4 and 6, that if the signal 2 or 2A is cleared neither the signal 7 nor the signal 7A can clear thereafter. Also, the signal 2A cannot clear when the signal 2 is cleared by reason of switch box or switch machine contacts associated with the track switch at which these signals are located, and in a similar way only one of the two starting signals 7 and 7A can clear at one time depending on the position of the track switch adjacent to which they are located. In other words, only one of the starting signals 2, 2A, 7 and 7A can clear at one time. From this it appears that if the control relay Z is energized and thereby permits clearing of either the starting signal 2 or the starting signal 2A that neither the starting signal 7 nor the starting signal 7A can clear even though the control relay Z^1 is energized thereafter. This feature of interlocking through the regular tumble down circuits of the usual A. P. B. system permits additional selective control to be obtained without additional line wires, and depends for its selectivity on the sequence in which the levers in the tower are moved. It thus appears that

it is desirable to be able to indicate in a convenient manner, as by a pilot light in the miniature track layout located in the dispatcher's office DO, the sequence in which 5 levers have been moved and the direction of traffic which has been set up by such lever movement.

In the system described in my prior application above referred to the entering signals 10 8 and 1 of the main track at opposite ends of a passing siding, such as the passing siding SD, are so interlocked that only one of these signals can assume the clear position at a particular time. By reason of this interlock, which is very similar to the interlock 15 between the starting signals at opposite ends of the single track section O, if one of these signals 1 or 8 is cleared the other signal is prevented from clearing, so that it is likewise 20 expedient to indicate in the tower the sequence in which the levers for controlling relays at opposite ends of a passing siding have been operated as far as clearing of signals on the main track of such passing siding 25 is concerned, and in accordance with the present invention provision is made for indicating such sequence of lever movement, that is, the sequence in which the levers have been moved for clearing signals permitting movement 30 of traffic over the main track of such passing siding; only is indicated. In other words, if one or the other of the switches of the passing siding SD is set for the siding, that is the levers associated with the switch 35 and signals for that end of the siding are moved to the left the sequence of lever movements is not indicated at all, although if it is desired to indicate the direction in which traffic may move over the siding, means may 40 be provided for accomplishing this end by obvious duplication of apparatus as readily appears hereinafter.

As readily appears each of the levers L is at the end of a single track section and is also 45 at the end of a passing siding, and in order to evidence two different conditions two relays 1R and 2R have been provided for each lever, these relays manifest that a lever has been moved from its normal position before the 50 next lever to the right has been moved from normal and the other of which manifests that the lever has been moved before the next lever to the left has been moved from normal.

Further, since it is proposed to indicate the 55 direction of traffic set up on the main track of a passing siding certain of the relays must not respond unless its lever has been moved to the main track position. Of these relays the relay 2R^o of the lever L^o, the relays 1R and 2R 60 of the lever L and the relay 1R¹ of the lever L¹ only have been shown. The manner in which these levers and relays control suitable direction indicators 20, 21, 22, and 23, which are preferably lamps, but may be electrically 65 operated banners or indicators of any type,

is more readily explained in describing the operation of the system.

Operation.—Let us assume that there is a west bound train standing on the main track 70 of the passing siding SD¹ and that it is desired to have this west bound train move through the main track of the passing siding SD, taking the main track in so doing, assuming also that there is no other train on this portion of the railroad. In order to clear the 75 signals properly for the train movement just mentioned, it is necessary for the operator to move to the right the contacts of the three levers shown in the order L¹, L and L^o. The operator will therefore move the contacts of lever L¹ toward the right to energize the control relay Z¹ to the right as shown, permitting clearing of the starting signal 7. The operator will next move the contacts of lever L toward the right energizing the control relay Z toward the right, but since the starting signal 2 by reason of its interlock with the signal 7 cannot clear, the signal 1 will clear. The operator next moves the contacts of lever L^o to the right, and in so doing energizes the control relay Z^o toward the right, the energization of which will permit the signal 7 at the west end of siding SD to clear, assuming 90 there is no train within the next block ahead of this signal and that no west bound traffic has been set up in the single track section ahead of this signal 7. This energization of the relay Z^o does however not allow the signal 8 to clear by reason of its interlock with the signal 1 of the same passing siding which is 95 already assuming the clear position. For a detailed description of the apparatus and control circuits used for interlocking these various signals, and for controlling them in accordance with the position of these control 100 relays and the order in which they have been operated, and traffic conditions in advance of such signals, reference may be had to my prior application above mentioned.

Let us now see which of the indicators 20, 110 21, 22 and 23, are rendered active in response to the aforementioned order of movement of the contacts of levers L¹, L and L^o toward the right. The movement of the lever L¹ in a clockwise direction closes an energizing 115 circuit for the relay 1R¹ which may be traced as follows:—beginning at the terminal B of a suitable battery, contact 12¹ of the lever L¹, wires 25 and 26, winding of the relay 1R¹, wire 27, back contact 28 of the relay 1R to the common return wire C connected to the midpoint of said battery. The energization of this relay 1R¹ in itself does not complete an energizing circuit for any one of the indicating lamps. Movement of the lever L in a clockwise direction, this being the second lever to be moved in the sequence of lever 120 movements assumed, closes an energizing circuit for the indicating lamp 20 which may be traced as follows:—beginning at the ter- 125

5 minal B, contact 12 of the lever L, wires 30 and 31, front contact 32 of the relay 1R¹, wire 33, signal lamp 20, wire 34, contact 11 of the lever L to common return wire C connected to the midpoint of the battery. The illumination of the indicating lamp 20 thus indicates that west bound traffic has been set up in the single track section O.

10 Movement of the lever L in a clockwise direction also completes an energizing circuit for the relays 2R as follows:—beginning at the terminal B of said battery contact 10 of the lever L, wires 36 and 37, winding of the relay 2R, wire 38, back contact 39, of the relay 15 2R^o to the common return wire C connected to the midpoint of said battery. In this connection it should be noted that movement of the lever L does not pick up the relay 1R because its energizing circuit is broken at the 20 back contact 28¹ of the relay 1R¹. In other words, the relay 1R and 1R¹ are so interlocked that if one of these relays is energized the other one cannot be picked-up, and by reason of this interlock it is possible to obtain an 25 indication as to the sequence of lever movements of two adjacent levers equipped with these interlocked indicating relays.

30 Energization of the relay 2R in response to movement of the lever L, as just explained, will not render one of the indicators 22 or 23 active until the lever L^o is moved. Movement of the lever L^o in a clockwise direction completes the following circuit for energizing the lamp 22:—beginning at the terminal B, contact 10° of the lever L^o, wires 43 and 44, front contact 45 of the relay 2R, wire 46 indicating lamp 22, wire 47, contact 11° of the lever L^o back to common return wire C connected to the midpoint of said battery. 35 40 For reasons already explained it should be noted that the relay 2R^o is not picked up in response to the movement of lever contacts of the lever L^o to the right, because the energizing circuit of this relay 2R^o is broken at the back contact 39¹ of the relay 2R.

45 Having now explained how the indicating lamps 20 and 22 are caused to be illuminated if the levers are moved in the sequence L¹, L and L^o in a clockwise direction let us observe which indicating lamps are illuminated if these three levers are moved in a counter-clockwise direction in the same sequence L¹, L and L^o. It will be noted that movement of the lever contact of the lever L¹ toward the left will complete the same energizing circuit for the relay 1R¹ as heretofore traced, except that the current is derived from N instead of B, and the movement of the contact of the lever L toward the left completes the same energizing circuit for the lamp 20 heretofore traced, except that the current flows in the opposite direction, but this will not change its indication. Movement of the contacts of lever L to the left, however, will 50 55 60 65 not pick up the relay 2R, therefore the indi-

cating lamp 22 the energizing circuit of which includes the contact 45 of these relay 2R is not illuminated.

Putting it briefly the indicating lamp 20 or 21 is illuminated if the levers L and L¹ 70 assume either of their extreme positions, the particular lamp of these lamps 20 and 21 illuminated depending upon the sequence on which these levers have been moved. Movement of the lever L^o in a sequence with respect to the lever L, the lamp 22 or 23 is energized if the contacts of both of these levers have been moved to the right extreme position, the particular lamp energized depending upon the sequence in which these 80 levers have been moved, and neither of these lamps 22 or 23 are energized if the contacts of either of the levers have been moved toward the left, or if both of these levers contacts have been moved toward the left. 85

Since the circuits for effecting illumination of the lamps indicating east bound traffic are exactly the same as those for indicating west bound traffic, like circuits and like contacts for east bound indication have 90 been assigned the same reference characters as those for west bound indication but having a distinctive exponent "one".

Having thus shown and described one 95 rather specific circuit arrangement for electrically indicating by incandescent electric lamps the sequence in which levers are operated, and in turn indicating the direction of traffic set up in the train dispatching system of the wayside signal indicating type, it is 100 desired to be understood that the specific circuit arrangement has not been selected in order to illustrate the exact circuit arrangement preferably employed in practicing the invention nor has it been selected to indicate 105 the scope of the invention; and it is desired to be understood that various changes, modifications and additions may be made to adapt the invention to the particular train dispatching system to which the invention is to be 110 applied, all without departing from the spirit or scope of the invention or the idea of means underlying the same except as demanded by the scope of the following claims.

What I claim is:—

1. In a system of train dispatching; the combination with a plurality of levers in a train dispatcher's office for controlling a plurality of signals in a manner so that the sequence of lever movement determines the direction in which traffic shall move; and means for indicating the sequence in which the levers of said system have been moved comprising, contacts on each of two adjacent levers closed when such lever assumes its abnormal operated position, a relay for each of said two adjacent levers, and a circuit for each of said relays including the said contacts for said lever and a back contact of the other relay, whereby the second operated lever cannot 115 120 125 130

pick up its relay, and indicating means controlled by said relays.

2. In a system of train dispatching; the combination with a plurality of levers in a train dispatcher's office in which each lever is used for controlling a plurality of signals in a manner so that the sequence of lever movements determines the signals for a particular lever that shall clear; and means for indicating the sequence in which the levers of said system have been moved comprising, contacts on each of two adjacent levers closed when such lever assumes its abnormal operated position, a relay for each of said two adjacent levers, and a circuit for each of said relays including the said contacts of said lever and a back contact of the relay of the adjacent lever whereby the second operated lever cannot pick up its relay, and indicating means controlled by said relays.

3. In a system of train dispatching; the combination with a plurality of levers in a train dispatcher's office for controlling a plurality of signals in a manner so that the sequence of lever movements determines the direction in which traffic shall move; and means for indicating the sequence in which the levers of said system have been moved from normal comprising, contacts on each of two adjacent levers closed when such lever assumes its abnormal operated position, a relay for each of said two adjacent levers, and a circuit for each of said relays including the said contacts for said lever and a back contact of the other relay, whereby the second operated lever cannot pick up its relay, an indicator, and a circuit for rendering said indicator active including a front contact of the relay of one lever and contacts of the adjacent lever closed when such adjacent lever assumes the abnormal position.

4. In a system of train dispatching; the combination with a plurality of levers in a train dispatcher's office, in which each lever is used for controlling a plurality of signals in a manner so that the sequence of lever movements determines the signals for a particular lever that shall clear; and means for indicating the sequence in which the levers of said system have been moved from normal comprising, contacts on each of two adjacent levers closed when such lever assumes its abnormal operation position, a relay for each of said two adjacent levers, and a circuit for each of said relays including the said contacts for the corresponding lever and a back contact of the relay of the adjacent lever, whereby the second operated lever cannot pick up its relay, an indicator, and a circuit for rendering said indicator active including a front contact of the relay of one lever and contacts of the adjacent lever closed when such adjacent lever assumes the abnormal position.

5. In a system of train dispatching; the

combination with a plurality of levers in a train dispatcher's office for controlling a plurality of signals in a manner so that the sequence of lever movements determines the direction in which traffic shall move; and means for indicating the sequence in which the levers of said system have been moved comprising, contacts on each of two adjacent levers closed when such lever assumes its abnormal operated position, a relay for each of said two adjacent levers, and a circuit for each of said relays including the contacts for the corresponding lever and a back contact of the relay of the adjacent lever, whereby the second operated lever of two adjacent levers cannot pick up its relay, an indicator for each of two adjacent levers for indicating which of said two levers has been moved from its normal position first, a circuit for each of said indicators each including contacts of its associated lever closed when such lever is in its abnormal position and a back contact of the relay of the adjacent lever.

6. In a system of train dispatching; the combination with a plurality of levers in a train dispatcher's office in which each lever is used for controlling a plurality of signals in a manner so that the sequence of lever movement determines the signals for a particular lever that shall be permitted to clear; and means for indicating the sequence in which the levers of said system have been moved comprising, contacts on each of two adjacent levers closed when such lever assumes its abnormal operated position, a relay for each of said two adjacent levers, and a circuit for each of said relays including the said contacts for said lever and a back contact of the relay of the adjacent lever, whereby the second operated lever cannot pick up its relay, an indicator for each of two adjacent levers for indicating which of said two levers has been moved from its normal position first, a circuit for each of said indicators each including contacts of its associated lever closed when such lever is in its abnormal position and a back contact of the relay of the adjacent lever.

7. In a system of train dispatching; the combination with a plurality of levers in a train dispatcher's office for controlling a plurality of signals in a manner so that the sequence of lever movement determines the direction in which traffic shall move; and means for indicating the sequence in which the levers of said system have been moved comprising, contacts on each of two adjacent levers closed when such lever assumes one particular extreme operated position, a relay for each of said two adjacent levers, and a circuit for each of said relays including the said contacts for said lever and a back contact of the relay of the other lever, whereby the second operated lever cannot pick up its relay unless the first operated lever was

- operated into the other extreme position, an indicator for each of two adjacent levers for indicating which of said two levers has first been moved to a particular extreme position, 5 a circuit for each of said indicators each including contacts of its associated lever closed when such lever assumes a particular abnormal position and a back contact of the relay of the adjacent lever.
- 10 8. In a system of train dispatching; the combination with a plurality of levers in a train dispatcher's office in which each lever is used for controlling a plurality of signals in a manner so that the sequence of lever 15 movements determines the signals for a particular lever that shall be permitted to clear; and means for indicating the sequence in which the levers of said system have been moved comprising, contacts on each of two 20 adjacent levers closed when such lever assumes one extreme operated position, a relay for each of said two adjacent levers, and a circuit for each of said relays including the said contact for said lever and a back contact of the other relay, whereby the second 25 operated lever cannot pick up its relay unless the first operated lever was operated into the other extreme position, an indicator for each of two adjacent levers for indicating which of said two levers has first been moved to a particular extreme position, a circuit for each of said indicators each including contacts of its associated lever closed when such lever assumes a particular extreme position and a back contact of the relay of the adjacent lever.
9. In apparatus for indicating the sequence in which levers of a train dispatching machine have been operated, the combination with two adjacent levers one controlling signals at one end of a stretch of track and the other controlling signals at the other end of a stretch of track, of two relays one of which if energized signifies that the levers have been operated in a certain sequence and the other of which if energized signifies that the levers have been operated in a different sequence, a circuit for one of said relays including a normally open contact of one of said levers and a back contact of the other relay, and a circuit for the other relay including a normally open contact of the other lever and a back contact of said one relay.

In testimony whereof I affix my signature.

SEDGWICK N. WIGHT.
